UNITED STATES PATENT OFFICE

2,157,990

WATCH BOX

Eugene Lux, New York, N. Y., assignor to The Gruen Watch Company, Cincinnati, Ohio, a corporation of Ohio

Application April 25, 1936, Serial No. 76,356

4 Claims. (Cl. 206—44)

This invention relates to watch display boxes and especially such boxes for wrist or strap watches in which wrist or strap watches are supported in a resilient shock-proof manner and 5 protected from dust, etc., and which boxes, when opened, provide a display for the watch so supported.

It is an object of my invention to provide a box for strap or wrist watches, in which means 10 is provided for resiliently supporting the watches to prevent injury thereof, during transit, due to shock and wherein the watches are supported resiliently within a rigid box and in spaced relation therefrom, the rigidity of the box preventing 15 injury of the watches due to crushing of the box and the resilient support of the watch in spaced relation with respect to the box preventing injury of the watches, due to the transmission of shock thereto from the rigid box.

It is a further object of my invention to provide such a box which will, when opened, provide an attractive display for the supported watch.

It is a further object of my invention to provide means in such a box for supporting a strap 25 or wrist watch in substantially the same manner as it will be supported upon the wrist of a wearer.

It is a further object of my invention to provide such a casing and display which may be used after the purchase of the contained watch, 30 either as a dust-proof case for the watch when not in use, or as a support therefor to be placed on an article of furniture such as a dresser or night table and which, when so placed, will support the watch in such a manner as to present 35 the face for facility of telling time.

It is a further object of my invention to provide supporting means in such a case, about 40 which a strap watch may be placed in any one of a plurality of positions about the circumference of the support in order that the position of the watch face may be widely varied for facilitating the reading of the time indicated thereby.

It is a further object of my invention to provide such a rigid case having padded inner side 45 members to prevent injury of the supported watch due to contact therewith.

These and other advantages will appear from the following description taken in connection 50 with the drawing.

In the drawing:

Figure 1 is a front elevational view of the box, closed;

Figure 2 is a side elevational view of the structure of Figure 1;

Figure 3 is a top plan view of the box, as shown in Figure 1;

Figure 4 is a top plan view of the box, opened;

Figure 5 is a side elevational view of the box, opened as in Figure 4; and

Figure 6 is a front elevational view of the box, half opened, the back portion of the box being in closed position and the position of the supported watch being indicated in dotted lines.

Referring to the drawing in detail, the base 1 is made of any suitable material and has rigidly secured thereto by means of an upstanding flange 2, a support 3 which is substantially in the shape of the letter C and which is preferably fashioned from resilient material, such as spring 10 steel. The members 1, 2 and 3 are preferably covered with suitable material such as velveteen for the sake of appearance and the prevention of scratching or marring of the watch supported thereon. The base 1 is suitably supported and 20 rigidly secured to a sub-base 4, to which is hingedly secured, by means of fabric hinges or the like, at opposite sides thereof, a pair of substantially identical annular front and back members, generally designated 5 and 6 respectively. 25 To the front member 5 is secured one part 7 of a snap fastener, while the other part 8 is secured by means of a strap 9 to the back member 6. The front member 5 and back member 6 are otherwise identical. The members 5 and 6 30 each comprise flat faces 10 having upstanding substantially vertically disposed flanges 11 secured to the arcuate portions of their circumferences. The flanges are integrally secured to the flat faces 10. The front and back members 35 5 and 6 and the sub-base 4 are provided with a suitable covering secured to their outer surfaces, the inner annular surfaces of the flanges 11 being covered in a like manner. Suitable padding 40 is preferably provided on the interior surface of each flat face 10 in order to prevent damage to a watch supported by the support 3 due to sidewise movement or vibration of the support 3 with respect to the back and front members 5 and 6 when the case is closed, the members 45 5 and 6 being then secured together by means 7, 8 and 9.

As will clearly appear from the drawing, the flanges 11 of the front member 5 and back member 6 are inwardly directed and closely contact one another when the case is closed, as is shown in Figures 2 and 3. Disposed around the outer peripheral portions of the flanges 11 and adapted to be supported in channels in the outer surface of each flange 11 is a metallic hoop 55

or band 12, which has the ends 14 thereof tightly crimped about the downwardly exposed end extremities of the respective flanges 11, as shown particularly in Figure 4. These bands extend 5 over the covering of the members 5 and 6 and tend to retain the coverings tight on the members and also to provide added rigidity for the members 5 and 6. The resilient support 3 has the exterior surface thereof spaced inwardly 10 from the flanges 11, as shown in Figure 6. By means of this relationship, the watch supported on the member 3 is resiliently held in spaced relation from the flanges 11 of the rigid front member 5 and back member 6 when the members 15 are held in closed position by the fastener means 7, 8 and 9.

Any damage due to sidewise vibration or movement of the member 3 with respect to the base 1 will be prevented by the padding of the inner 20 surfaces of the flat faces 10. Furthermore, only the side frame portions of the watch will be exposed to or will contact with the padded flat faces 10. Due to the resiliency of the member 3, it will readily accommodate strap watches of 25 widely differing strap lengths, and furthermore the rigidity of the support of the strap watch and the spacing thereof from the flanges 11 of the front member 5 and back member 6 in the closed 30 position of the case may be varied by adjustment of the length of the watch strap.

I have shown a substantially flattened portion 15 on the member 3 for the accommodation of an elongated strap watch case, and it is to be understood that the size and shape of the 35 member 3 may be widely varied in order to accommodate strap watches of different proportions and that the case is also susceptible of use as a display and container for various other articles of jewelry, such as bracelets or the like. 40 For accommodation of watch straps of extreme thickness, or of such chains, bracelets or the like, the length of the upstanding flange 2 will be varied, as desired.

It is to be understood that the above description 45 and the illustration in the drawing is merely illustrative and in no wise limiting and that the shape, contour and proportions of the various parts of my case are subject to wide variance in the practice of my invention, and it will be understood that I desire to comprehend within my 50 invention such modifications as come within the scope of the claims and the invention.

When I refer to "case", I refer to the box of 55 this invention and not to a watch case. I use the two terms interchangeably.

Having thus fully described my invention, what I claim as new and desire to secure by Letters Patent is:

1. A container for a wrist watch and strap 60 comprising a flat base adapted to be supported

on a substantially horizontal surface, a plurality of covers, a plurality of hinges for said covers, said hinges being attached to said base on opposite sides thereof and supporting said covers for swinging movement, a supporting member of 5 curvilinear shape, means for attaching said curvilinear member to said base in spaced relation thereto between said hinged covers and in upright position, said hinges being located below said attaching means, and said covers being constructed 10 and adapted to completely enclose said curvilinear member when they are in closed position.

2. A container for a wrist watch and strap comprising a flat base adapted to be supported on a substantially horizontal surface, a plurality of 15 covers, a plurality of hinges for said covers, said hinges being attached to said base on opposite sides thereof and supporting said covers for swinging movement, a resilient supporting member of curvilinear shape, means for attaching 20 said curvilinear member to said base in spaced relation thereto between said hinged covers and in upright position, said hinges being located below said attaching means, and said covers being constructed 25 and adapted to completely enclose said curvilinear member when they are in closed position.

3. A container for a wrist watch and strap comprising a flat base adapted to be supported on a substantially horizontal surface; a plurality 30 of covers, a plurality of hinges for said covers, said hinges being attached to said base on opposite sides thereof and supporting said covers for swinging movement, a supporting member of curvilinear shape, vertically extending means for 35 attaching said curvilinear member to said base in spaced relation thereto between said hinged covers and in upright position, said hinges being located below said attaching means, and said covers being constructed and adapted to completely 40 enclose said curvilinear member when they are in closed position.

4. A container for a wrist watch and strap comprising a flat base adapted to be supported on a substantially horizontal surface, a plurality 45 of covers, a plurality of hinges for said covers, said hinges being attached to said base on opposite sides thereof, and supporting said covers for swinging movement, a supporting member of curvilinear shape, means including a flange 50 mounted adjacent one side edge of said curvilinear member for attaching said curvilinear member to said base in spaced relation thereto between said hinged covers and in upright position, said hinges being located below said attaching means, and said covers being constructed and adapted to completely 55 enclose said curvilinear member when they are in closed position.
